Primary Examiner — Ian Simmons*Assistant Examiner* — Carissa C Fitts(74) *Attorney, Agent, or Firm* — McCarter & English, LLP**CLAIM**

(57) The ornamental design for a scalpel handle, as shown and described.

DESCRIPTION

FIG. 1 is a side elevation view of a scalpel handle.

FIG. 2 is a rear perspective view of the scalpel handle; and,

FIG. 3 is a front elevation view of the scalpel handle.

The broken line showing is for environmental purposes only and forms no part of the claimed design.

It is designed to receive a scalpel blade and be used by medical personnel during surgical procedures.
